CLAIM

The ornamental design for a personal heating or cooling device lid, as shown and described.

DESCRIPTION

FIG. 1 is a front elevation view of the personal heating or cooling device lid showing our new design;

FIG. 2 is a right side elevation view of the personal heating or cooling device lid;

FIG. 3 is a rear elevation view of the personal heating or cooling device lid;

FIG. 4 is a left side elevation view of the personal heating or cooling device lid;

FIG. 5 is a top plan view of the personal heating or cooling device lid;

FIG. 6 is a bottom plan view of the personal heating or cooling device lid;

FIG. 7 is a top front left side isometric view of the personal heating or cooling device lid;

FIG. 8 is a top front right side isometric view of the personal heating or cooling device lid;

FIG. 9 is a bottom front left side isometric view of the personal heating or cooling device lid; and,

FIG. 10 is a bottom front right side isometric view of the personal heating or cooling device lid.

In the drawings, the broken lines depict unclaimed subject matter only and form no part of the claimed design.

1 Claim, 5 Drawing Sheets
